Primary Examiner — Kendra Leslie Hamilton

(74) Attorney, Agent, or Firm — Sheridan Ross P.C.

(57) CLAIM

The ornamental design for a pacifier, as shown and described.

DESCRIPTION

FIG. 1 is a front perspective view of a pacifier;

FIG. 2 is a rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a front perspective view of the pacifier of FIG. 1 interconnected to a pacifier cover; and,

FIG. 10 is a left elevation view of the pacifier of FIG. 1 interconnected to a pacifier cover.

In the drawings, the equal-length broken lines depict portions of the pacifier that form no part of the claimed design. The broken lines showing a pacifier cover in FIGS. 9 and 10 depict environmental structure that forms no part of the claimed design. All broken lines form no part of the claim.

1 Claim, 10 Drawing Sheets
